[57] CLAIM

The ornamental design for a telephone terminal apparatus, as shown and described.

DESCRIPTION

FIG. 1 is a top plan view of a telephone terminal apparatus showing my new design;

FIG. 2 is a bottom plan view;

FIG. 3 is a front elevational view;

FIG. 4 is a right side elevational view, the left side being a mirror image thereof; and,

FIG. 5 is a rear elevational view thereof.
